H. DAVIES

ELECTRICAL FUSE

Filed Oct. 21, 1919

INVENTOR:

HOWARD DAVIES,

*by John C. Raigh,
Attorney.*

UNITED STATES PATENT OFFICE.

HOWARD DAVIES, OF PHILADELPHIA, PENNSYLVANIA.

ELECTRICAL FUSE.

Application filed October 21, 1919. Serial No. 332,213.

To all whom it may concern:

Be it known that I, HOWARD DAVIES, a citizen of the United States, residing at Philadelphia, in the county of Philadelphia and State of Pennsylvania, have invented a certain new and useful Improvement in Electrical Fuses, whereof the following is a specification, reference being had to the accompanying drawing.

10 My invention relates to fuses of the class including a tubular casing of insulating material having metallic terminals at its opposite ends adapted to detachably secure a strip of fusible metal; said terminals also

15 having means to electrically connect said fuse strip with conductors leading to and from said casing.

As hereinafter described, my invention includes a specific construction and arrangement of said terminals, comprising wedge abutments which are respectively fixed in said casing at opposite ends thereof, and wedges which are movable in said casing, in opposition to the respective abutments, to

25 detachably secure the opposite ends of a fuse strip between them.

Moreover, my invention includes the various novel features of construction and arrangement hereinafter more definitely specified.

In the drawing; Fig. I is a side elevation of a fuse embodying my invention.

Fig. II is a longitudinal sectional view of said fuse, taken on the line II, II in Fig. I.

30 Fig. III is a lower end view of said fuse as shown in Fig. I.

Fig. IV is a transverse sectional view of said fuse, taken on the line IV, IV in Fig. II.

Fig. V is a transverse sectional view of

40 said fuse, taken on the line V, V in Fig. II.

Fig. VI is a face view of the cap washer shown in Fig. III, but detached from the fuse structure.

In said figures; the cylindrical tubular casing 1 is composed of insulating material, preferably vulcanized fiber, and has the metallic screw nipples 2 threaded therein at its opposite ends and fastened with the respective set screws 3 which also hold the semi-cylindrical metallic terminal members 5 which have their inner faces 6 extending in planes which are oblique to the axis of said casing 1, so as to afford respective wedge abutments, in opposition to the parallel plane inclined faces 8 of the respective complementary semicylindrical wedges 9. Said

wedges 9 are movable axially in said casing 1, to clamp the respective ends of the fuse strip 10 between said wedges 9 and said wedge abutments 5.

60 As indicated in dotted lines in Fig. I, said fuse strip 10 is much wider at its ends which are engaged with the wedge elements aforesaid than at its intermediate portion; the latter being of a cross sectional area which is precisely predetermined in accordance with the rated capacity of the fuse. Said wedges 9 may be pressed into the position shown in Fig. II, by the fingers of the operator, the inclination of their plane faces 65 being such as to afford adequate clamping action throughout the entire surfaces of said fuse strip 10 which are engaged by the respective terminals.

65 However, I find it convenient to provide each of said wedges with external grooves 11 which are preferably helically inclined, as indicated in dotted lines in Fig. I, to facilitate their progressive engagement by the tip of a screw driver, or any other similar implement by which the operator may find it convenient to withdraw said wedges from their clamped position shown. To prevent accidental displacement of said wedges, I provide the screw caps 12 which are respectively engaged with said nipples 2 and which contain the cap washers 13 which bear upon the outer ends of said wedges 9. Each of said washers 13 has a diametrical slot 14, best shown in Fig. VI, through 70 which I prefer to extend the ends of the fuse strip so that the latter may be marked, as indicated in Fig. III, to show the rated capacity of the fuse, for instance, as shown in said figure, "200 amps. 250 volts." 75 Therefore, it may be observed that said nipples 2 comprise not only means arranged to engage said terminal members in the casing but also means engaging said screw caps on said casing and preventing retraction of 80 said wedges from clamped position.

I am aware that it is the usual practice to mark the casings of fuses of this general class so as to indicate the capacity of the fuse strips for which they are designed to be 85 used. However, I find that, very often, and particularly in the case of renewal of fuse strips, fuse strips of less capacity are inserted in the casings thus marked; with the result that the subsequent user thereof is 90 misled by the marking upon the exterior of the casing as to what is the actual capacity

of the structure as a fuse. Therefore, the provision of means in my improved fuse above described, whereby the actual capacity of the fuse strip itself is manifested upon 5 the exterior of the casing, is of great practical advantage.

In the form of my invention chosen for illustration; the terminals 5 are provided with respective electrical conducting elements 16, in integral relation therewith, which serve as blades for detachable electrical connection between opposite spring plates, of any suitable construction, which are indicated at 17 in Fig. II. I am aware 10 that it is not new to provide a fuse of the general class of my invention with terminal blades, but, as ordinarily constructed, they are movable with respect to the terminals and, therefore, get out of alinement and are 15 otherwise troublesome, because they are free to rotate, whereas, in accordance with my improved construction above described, the blades 16 are continuously maintained in alinement with each other by the same 20 screws 3 which retain the terminal members 5 in stationary relation with said casing 1.

As best shown in Fig. VI, the diametrical slot in the cap washer 13 is so shaped as to permit the extension of the blade 16 therethrough, as in Fig. III, and said blades 16, being stationary in said casing 1, as above described, thus prevent the rotation of said washers 13 when said caps 12 are rotated to apply and remove them with respect to said 30 nipples 2. However, it is to be understood that my invention is not limited to the provision of such conducting elements as the blades 16 upon the terminals 5. The blades 16 may be omitted and any other suitable 35 conductors be extended through the openings in the cap washers 13, in electrical connection with said terminals 5. For instance, ordinary cylindrical wires may be extended into said caps 12 through the respective 40 openings 14 and be clamped by rotation of said caps with the ends of the wires between the cap washers and the adjacent ends of the wedges 9.

I also find it convenient to provide said 50 casing 1, with a removable lining 18, of insulating material, for instance, asbestos sheeting.

Therefore, I do not desire to limit myself to the precise details of construction and arrangement herein set forth, as it is obvious 55 that various modifications may be made therein, without departing from the essential features of my invention as defined in the appended claims.

60 I claim:

1. In an electrical fuse structure; the combination with a cylindrical tubular casing of insulating material, having internal screw threads at its opposite ends; of metallic screw nipples threaded in said casing at its 65

opposite ends; means fastening said nipples in said casing, including respective screws extending radially through said casing and nipples; substantially semicylindrical metallic terminal members held in said nipples by said screws and having their inner faces extending in planes which are oblique to the axis of said casing, affording respective wedge abutments; wedges respectively axially movable in said casing in opposition to said wedge abutments, having their inner faces respectively inclined parallel with the inclined faces of said abutments; said wedges having means to facilitate their withdrawal including grooves in the respective wedges extending obliquely with respect to the axis of said casing in the perimeters of said wedges; whereby said wedges are adapted to clamp a fuse strip between them and their respective abutments; screw caps 80 respectively fitted to the outer ends of said nipples; cap washers, fitted in said caps in opposition to the outer ends of said wedges, and having respective openings for electrical conductors; electrical conducting elements, 85 respectively in integral relation with said wedge abutments and adapted to extend through the openings in said cap washers; said conducting elements being formed as plane blades which are held in alinement 90 with each other by said abutments; and a fuse strip extending in said casing, but clamped by said wedges, having its opposite ends extending through said cap washers.

2. In an electrical fuse structure; the combination with a tubular casing of insulating material, having internal screw threads at its opposite ends; of metallic screw nipples threaded in said casing at its opposite ends; means fastening said nipples in said casing, 100 including respective screws extending radially through said casing and nipples; substantially semicylindrical metallic terminal members held in said nipples by said screws and having their inner faces extending in planes which are oblique to the axis of said casing, affording respective wedge abutments; wedges respectively axially movable in said casing in opposition to said wedge abutments, having their inner faces respectively inclined parallel with the inclined faces of said abutments; whereby said wedges are adapted to clamp a fuse strip between them and their respective abutments; screw caps 110 respectively fitted to the outer ends of said nipples; and cap washers, fitted in said caps in opposition to the outer ends of said wedges, and having respective openings for electrical conductors.

3. In an electrical fuse structure; the combination with a tubular casing of insulating material; of metallic screw nipples in said casing at its opposite ends; means fastening said nipples in said casing, including respective screws extending through said casing 120

and nipples; substantially semicylindrical metallic terminal members held in said nipples by said screws and having their inner faces extending in planes which are oblique to the axis of said casing, affording respective wedge abutments; wedges respectively axially movable in said casing in opposition to said wedge abutments, having their inner faces respectively inclined parallel with the inclined faces of said abutments; whereby said wedges are adapted to clamp a fuse strip between them and their respective abutments; screw caps respectively fitted to the outer ends of said nipples; and cap washers, fitted in said caps in opposition to the outer ends of said wedges, and having respective openings for electrical conductors.

4. In an electrical fuse structure; the combination with a tubular casing of insulating material; of metallic screw nipples in said casing at its opposite ends; metallic terminal members held in said nipples and having their inner faces extending in planes which are oblique to the axis of said casing, affording respective wedge abutments; wedges respectively axially movable in said casing in opposition to said wedge abutments, having their inner faces respectively inclined parallel with the inclined faces of said abutments; whereby said wedges are adapted to clamp a fuse strip between them and their respective abutments; and screw caps respectively fitted to the outer ends of said nipples.

5. In an electrical fuse structure; the combination with a tubular casing of insulating material; of metallic terminal members held in said casing having their inner faces extending in planes which are oblique to the axis of said casing, affording respective wedge abutments; wedges respectively axially movable in said casing in opposition to said wedge abutments, having their inner faces respectively inclined parallel with the inclined faces of said abutments; said wedges having means to facilitate their withdrawal including external grooves in the respective wedges; whereby said wedges are adapted to detachably clamp a fuse strip between them and their respective abutments; caps removably fitted at the opposite ends of said casing; and a fuse strip extending in said casing, clamped by said wedges, having one end extending through one of said caps.

6. In an electrical fuse structure; the combination with a tubular casing of insulating material; of metallic terminal members held in said casing having their inner faces extending in planes which are oblique to the axis of said casing, affording respective wedge abutments; wedges respectively axially movable in said casing in opposition to said wedge abutments, having their inner

faces respectively inclined parallel with the inclined faces of said abutments; whereby said wedges are adapted to detachably clamp a fuse strip between them and their respective abutments; caps removably fitted at the opposite ends of said casing; and a fuse strip extending in said casing, clamped by said wedges, having one end extending through one of said caps.

7. In an electrical fuse structure; the combination with a tubular casing of insulating material; of metallic terminal members held in said casing, having their inner faces extending in planes which are oblique to the axis of said casing, affording respective wedge abutments; wedges respectively axially movable in said casing in opposition to said wedge abutments, having their inner faces respectively inclined parallel with the inclined faces of said abutments; whereby said wedges are adapted to detachably clamp a fuse strip between them and their respective abutments; each end of said casing having a screw thread concentric with the casing axis, and means arranged to engage said terminal members; and screw caps carried by said casing, having means normally engaging said terminal members and preventing retraction of said wedges from clamped position; whereby it is necessary to rotate the respective caps before the respective wedges can be removed to release the fuse strip clamped thereby.

8. In an electrical fuse structure; the combination with a tubular casing; of a metallic terminal member fixed in said casing having an inner plane face extending in acute angular relation to the longitudinal axis of said casing, affording a wedge abutment; a wedge axially movable in said casing in opposition to said wedge abutment; whereby said wedge is adapted to detachably clamp a fuse strip against said abutment; caps on said casing normally preventing retraction of said wedges from clamping position; and means on said casing, engaging said caps; whereby it is necessary to turn said caps upon said casing, in coaxial relation therewith, to release the fuse strip clamped by said wedges.

9. In an electrical fuse structure; the combination with a tubular casing having a wedge abutment with a plane face inclined in acute angular relation to the axis of said tube, and a contact blade member, having opposite parallel plane faces in integral relation with said abutment; of a wedge adjustable axially in cooperative relation with said abutment, arranged to clamp a fuse strip in electrical connection with said blade.

In testimony whereof, I have hereunto signed my name at Philadelphia, Pennsylvania, this eighth day of September, 1919.

HOWARD DAVIES.
